DESIGN FOR A CARPET OR SIMILAR ARTICLE

Herman Kluesing, Chicago, Ill., assignor to Carson Pirie Scott & Co., Chicago, Ill., a corporation of Illinois

Application February 7, 1940, Serial No. 90,109

Term of patent 7 years

To all whom it may concern:

Be it known that I, Herman Kluesing, a citizen of the United States, and a resident of Chicago, Illinois, have invented a new, original, and ornamental Design for a Carpet or Similar Article, of which the following is a specification, reference being had to the accompanying drawing forming part thereof, in which the figure is a plan view of a carpet showing my design.

I claim:

The ornamental design for a carpet or similar article, substantially as shown.

HERMAN KLUESING.
